APPARATUS FOR TREATING MATERIAL

Sumner H. Williams, Charlotte, N. C.

Application February 26, 1942, Serial No. 432,499

5 Claims. (Cl. 68—175)

The purpose of this invention is to produce controlled uniformity of dyed or chemically treated lots of material by a continuous operation. From a control standpoint, we have found that a suitable way to carry out this function is to first apply the colors or chemicals to the material and then carry either in a continuous operation, or as a separate operation, for further dyeing or developing, to the unit such as designed, in order to further properly fix or fasten the dyestuffs to the material or fibres. This procedure is best explained on the order of a continuous vat pigment form of dyeing. We use the vat colors in citing this instance, but the same is true of any of the other groups of colors or chemicals that require additional development, reduction or fixation in order that they may be dyed or treated to obtain their maximum fastness. The vat colors in their pigment form have little or no affinity and, therefore, can be applied very uniformly over the material to be dyed, in this form, but require further reduction treatment so that they may be properly affixed to the material to produce their rated fastness.

One object of this invention is to take such pretreated material containing these pigment dyes or chemicals, or other coloring matter, to a developing or dyeing unit, such as shown, either in a wet or dry state and gravity feed a treating solution with the material through a confined channel area arranged so that the treating fluid follows the material in an even manner, and due to the close confinement, the vat pigments in the process of becoming solubilized or reduced are prevented from bleeding off into a wide area of solution, as this solution travels with the material, closely confined. The stripping off action or bleeding is held to a very close minimum and produces results from a dyeing standpoint that cannot be obtained by the present methods in use, such as the adding of pre-dissolved dyes to a dye-bath.

By pre-treating the material with this coloring matter, it is possible to use types of dyestuffs that vary considerably in their rates of exhaust or have different chemical structures, and produce even dyeing effects by such mixtures, which are uniformly controlled. If such mixtures of colors were dissolved and added to a tank of any structure as the material would pass through, the fastest dyeing types would be absorbed first out of the solution, leaving behind the less substantive types and produce an uncontrollable dyeing factor. By carrying such mixtures or groups of colors that have already been adhered to the ma-

terial, such as by padding them on or by any other means, for further dyeing and development, they may be carried with the material, together with the fluid, so that no remaining color is left back in any stationary part of the treating liquid. The treating liquid is forced by gravity to flow concurrent with the material until the dyeing or chemical action has been completed.

It has taken many years of research to devise 10 a movable treating fluid in a confined area to produce the results, as explained.

The following description relates to my invention 15 in the process and apparatus of treating material. More particularly it deals with chemical

15 treatment whether bleaching, dyeing, washing or otherwise of a continuous web of textile fabric. The web or fabric or material, as mentioned here, may be in any physical form, such as thread or 20 yarn or yarns grouped together, known as warps.

20 Textile fabrics have been made by weaving, knitting or otherwise, yarn thread or other strands in great varieties of materials thus the fibers which are spun together to form the material may be animal fibers such as silk, wool and 25 mohair, minerals fibers such as asbestos, sodium silicate and similar forms or may be of vegetable origin such as natural fibers of cotton, flax and synthetic fibers as cellulose acetate, viscose or cuprammonium and all other forms of synthetic

30 silk-like materials as nylon and casein fibers. Frequently these materials are made up not only of a single type of fiber but a mixture of various materials such as above described.

Chemical treatment of such mixed fibers for 35 bleaching, dyeing or otherwise conditioning, must take into consideration differences in reaction by the several types of fibers and different periods of time or conditions which must be observed in producing a satisfactory uniform product.

40 This invention proposes a process for the chemical treatment of such textile fabrics regardless of their particular constitution and applicable for many operations such as bleaching, dyeing and the like.

45 In many instances satisfactory treatment of the material is dependent upon avoiding unnecessary exposure to the air either of the reacting solution or of the fabric undergoing treatment. In the treatment of a continuous web of material

50 it is important to insure even and uniform exposure of the material throughout its length to the reacting solution or solutions. In like manner it is necessary to bring the reacting solution into the most intimate contact with the fabric until 55 the desired chemical and physical actions take

place between the material and ingredients carried by the treating liquid. This invention provides for the dyeing, bleaching or other chemical treatment of a continuous web of material in a manner that allows the material to be treated evenly on all sides as the layer of treating liquid completely surrounds the material and is held in close contact to the latter by the particular construction of narrow channels through which the material to be treated moves and thus is brought into contact with the treating fluid which is also in motion either in the direction of the material or in the opposite direction. This brings about faster chemical treatment due to utilizing the full area of this liquid traveling in motion with the material.

This procedure maintains a positive control and a desirable low ratio of treating liquid to the material under treatment. By the material being surrounded with such a thin layer of liquid the ingredients which are either dissolved or held in suspension in the liquid are forced by close contact to react evenly over the material for the purpose intended and without loss. This is in direct contrast to the prevailing practice which either forces the chemical solutions through stationary held materials or conversely agitates the material in a normally stationary treating solution.

My invention uses a basically different principle, that of causing the material to travel through the machine so that the material is submerged in a minimum quantity of the liquid so arranged as to bring the material in close contact with the dyes, bleaching agents or other chemicals. At the same time the treating liquid is caused to travel in contact with the fabric until completion of the desired chemical reaction.

To define more clearly the treatment of material either chemically or with dyestuffs, inasmuch as the chemicals or coloring matter may react not only chemically but physically, this invention covers the mechanical and physical reactions between the material to be treated and the ingredients, which are brought in contact with it, contained in the fluid, as these ingredients in the fluid may be chemically inert and are mechanically forced on the material by either close contact in processing same by the method stated.

To properly carry out my process for the chemical treatment of a continuously advancing web of textile fabric, I have designed an improved apparatus capable of successfully treating the material and in particular dyeing it by any one of the different types of dyes. The apparatus is equally advantageous for bleaching and other chemical treatments than dyeing.

A further object of my invention is to provide an apparatus by which the material may be treated to a blend of colors giving a desired shade. This treatment may be simultaneous or successive when the dyes have different affinities for the fiber treated or adhere to the material at different rates of speed. By applying these colors together with the material or by first treating the material with these colors and then passing them through the apparatus for further development, the forced contact of the reacting materials with the fabric in a confined area and subject to common motion, the dyes are prevented from exhausting as they would react when applied from stationary solutions.

In particular the reacting chemicals with which it is intended to treat the fabric, may be

fed to the apparatus either at the point of entrance or at any subsequent stage, or separate reagents may be added at separate points in order to bring the reaction to completion at the point of delivery.

A still further object of my invention is to maintain a desired control of the temperature of the material and reacting liquid.

Among the objects of my invention is to economize the chemical agents used and to guard them from unnecessary exposure to oxidization.

As an illustration of the preferred form of apparatus by which my invention may be carried out, I have shown a typical installation in the accompanying drawings in which

Fig. 1 is a longitudinal vertical section on the line 1—1 of Fig. 2 showing an apparatus for effecting chemical treatment of a web of textile fabric by a treating liquid;

Fig. 2 is a top plan view of the same and Fig. 3 is a side elevation showing the apparatus arranged to receive the web to be treated.

Broadly speaking the invention consists in providing a restricted channel closely conforming to the area of the fabric to be treated, permitting the movement of the treating liquid along with or contrary to the course of the web being treated and with minimum exposure to the air.

Such an arrangement is accomplished with a tank 4 which is composed of suitable material to withstand the chemicals in the treating solutions. This tank has heating means such as the coil 5 or analogous means by which the water or other fluid in the tank may be kept at the desired temperature most satisfactory for carrying out the chemical treatment.

The tank has an inner wall or lining 6 by which the tank becomes a heating water jacket. This lining is formed with vertical partitions or dams. I have shown two such transverse hollow partitions 7 and 8 extending upwardly in the tank. The transverse partition 9, is slightly lower than the top of roll 20, preceding this partition. Fig. 1 shows that the fluid travels over the first top roll 20, following the material into the second channel, of which the top of the second roll 20, is slightly lower than the first, allowing the liquid to cascade from one channel to the other. The dam 9, slightly lower than roll 20, allows for a continuation of the flow of liquid into the next series of channels, the cascade of liquid flowing over the top of each roll 20, until reaching the exhaust level 18.

At the head or entrance end of the tank the inner wall or lining 6 rises above the tank to form a funnel or chute 15 which in Fig. 2 is shown to extend the full width of the tank and to permit the entrance of the web of fabric 16.

The chemical solution is added in desired quantity to the funnel 15 through the inlet pipe 17. After flowing through the tank the spent chemical liquid overflows through the pipe 18.

Suitably journaled in the side walls of the tank as shown at 19 in Fig. 2, is a series of rolls 20. A roll 20 surmounts each partition 7, 8, 10, 11, 13, and 14 and has a diameter slightly greater than the partition. Each of the several rolls 20, is slightly lower than its preceding roll, so that the liquid flowing over the top of the first roll 20, flows through and under the baffles, following the material, and cascades over the second roll 20, continuing over dam 9 and in the same manner throughout the balance of the machine to point 18 where the spent liquids are exhausted.

A series of baffles 21 are suspended by means of

bars 22 from the top of the tank and into the wells 23 between the several partitions, dams and the walls of the tank. These partitions extend below the full width of the tank. They have a transverse width slightly less than the wells in which they are suspended thus providing narrow passageways for the web and the surrounding liquid.

The lower end of each baffle has a pair of standards 24 in which is journaled a roller 25. This roller has a diameter slightly greater than the transverse width of the baffle. The diameters of the rolls 20 and 25 are such that the web 16 passes through the narrow channels between the baffles and the adjacent partitions, dams or tank walls.

Suitably mounted on standards 26 on the side of the tank are rolls 27 and 28 arranged in superposed pairs. The first pair of rolls 27 surmounts the dam 9 and the lower roll 28 has a diameter such that the web rises upwardly along one side of the dam and down the other side equally spaced between the vertical faces of the dam and the adjacent baffles.

A second pair of rolls 29 and 30 is mounted above the tank and the dam 12 in the same manner and for the same purpose.

At the discharge end of the tank a third pair of rolls 31 and 32 is mounted to receive the web as it rises from the narrow space between the baffle 21 and the wall of the hollow tank 6.

Each pair of rolls is driven with suitable driving means provided to rotate the rolls advancing the material through the machine, their purpose being to cut down the strain and lessen the tension on the fabric in its travel through the apparatus.

Figure 3 illustrates the method of starting the chemical treatment. The requisite quantity of chemical solution having been run into the wells 23, a web 16 is passed between the pairs of rolls 27, 28, 29, 30, 31 and 32.

The baffles are then lowered, either simultaneously or successively into their respective wells. This serves to festoon the web so that it passes down near the end wall 6 of the tank around the roller 25 of the first baffle and thence around the roller 20 above the partition 7. Each baffle 21 establishes a corresponding festoon in its respective well.

It will be apparent that the web delivered from the well in advance of the dam 9 is carried up to the first pair of rolls before festooning through the wells between the dams 9 and 12. In like manner the web passes through the second rolls before festooning in the wells between dam 12 and the third pair of rolls.

The treating fluid reaches a level above the partition 7, over top roll 20 and the level of film of liquid over this roll is governed by the speed of the fluid fed into the machine at 17. The speed of the travel of the fluid with the material is, therefore, regulated at point of entry 17, and point of exhaust 18. As the solution cascades over the top of each roller and down through the channels with the material, the speed of flow is governed at the point of entry, and the height of film above the rollers 20 is governed at the point of exhaust 18.

As the web is drawn through the apparatus it will carry with it a thin narrow surrounding stream of treating liquid modified only by the wringing action of the rolls. Fresh liquid is fed into the funnel or hopper 15 as the spent liquid is discharged from the overflow 18.

The surface of the treating liquid exposed to the air is limited to that area between the baffles

and over the dams. This is a very small ratio compared with the area of fabric being treated. Consequently there is a minimum of deterioration of the treating liquid which is very important where the latter must be protected against oxidation.

In some instances separate dye solutions may be introduced successively. For example a dye which operates slowly may be introduced with the web and followed by the introduction of a more rapidly operating dye into the well between the dam 9 and partition 10. Thus both dyes will have completed their reaction as the web leaves the final well.

15 Some reactions may suggest the advisability of drawing the web through the apparatus in the reverse direction to the flow of liquid reagent. This of course will be easily accomplished in the apparatus as described.

20 Likewise the several wells may be arranged horizontally so that the material and fluid may be caused to traverse back and forth in a horizontal direction.

Instead of heating the water bath of the tank 25 by means of the coil 5, I may also use steam, gas or electrical units. Such heating means may also be applied to the removable baffles.

The process of chemically treating the fabric in this apparatus may be carried out for various

30 objects. Thus the process is peculiarly adapted for all types of vat or leuco colors which due to their oxidizing properties are dyed to the best advantage in baths or solutions that are not exposed to the air. Such colors are indanthren 35 blue BCS—color index No. 1114, and caledon Jade green—color No. 1101. With such colors the baffling of the path gives a maximum area of fabric in contact with the solution and a minimum exposure of liquid. This consequently minimizes the required amounts of reducing chemicals such as sodium hydrosulphite.

It will be evident that similar advantages are obtained by confining bleaching solutions such as 45 sodium or hydrogen peroxide and solution of chlorine incidental to carrying out a bleaching operation.

As an example of continuously dyeing with direct or substantive dyes I have carried out the 50 process with diamine sky blue FF—color index No. 518, and chrysophenine—color index No. 365, obtaining all depths of shades. The material was first treated with a direct color by passing the material through a bath containing the color in 55 a water solution. The fabric was then taken to the illustrated apparatus either wet or dry where the dyeing and developing was accomplished by the further treatment of the material with the solution of common salt. This solution traveled in the thin area with the material at 200° F. 60 forcing the proper fixation of the dyestuff to the fiber until the reaction was completed. The application of this group of colors surpasses in time and control the conventional methods in use for applying this group of dyestuffs.

The second method used in applying the direct colors is by entering the untreated material, containing no dyestuffs, to the machine and feeding simultaneously the dissolved color along with the 70 necessary chemicals, and the color and material traveling together until the dyes are absorbed out of the fluid onto the material to a point where the dyeing action is complete, adding, if necessary, solutions of common salt or other chemicals that may be necessary to accelerate the dyeing

ction between the material and the colors held in the fluid.

Sulphur dyestuffs such as immedial green—color index No. 1106, and immedial orange C—color index No. 949, are applied in the same manner, that is, either by treating the fabric first with the unfixed dyestuff either wet or dry or by adding the dyestuff with the fabric in fixed proportions to the apparatus, adding the requisite chemicals such as sodium sulphide and common salt to the treating liquid and causing the fabric and liquid to travel together in close contact. Here again the dyeing action is completed in a shorter space of time with a more complete control of final shade and less oxidation of the dyestuff.

In applying diazo or developed dyes such as primuline, color index No. 812, or diamine black BH—color index No. 401, the first step is carried out in the same manner as with direct or substantive dyestuffs but as these colors necessitate a further treatment, necessary to produce their desired fastness and true shade, they are further chemically treated. Thus the fabric which already contains the fixed dyestuff is passed through the apparatus containing the solution with sodium nitrite and either hydrochloric or sulphuric acid. For the production of the final shade the fabric may be treated further in the same apparatus after rinsing, by applying such developers as beta naphthol or other suitable chemicals.

I have used this process also for the dyeing of vat colors shown by color indexes such as anthra yellow GC—color index No. 1095, indanthren olive R—color index No. 1150, bromide indigo MLB/4B—color index No. 1184, and helindone pink BN—color index No. 1211. These include the anthraquinone, the indigoid, both bromide and the thio indigoid types, including synthetic indigo—color index No. 1177, or hydron blues—color index No. 969 and 971, carbasols, and the water soluble vat colors or leuco vats such as known to the trade as algosols or indigosols (caledon jade green index color No. 1101). All these groups have been dyed successfully by this process by treating the material to be dyed with these dyes in pigment or in soluble form and entered into the continuous developing and dyeing unit, either wet or dry, into which is fed simultaneously the necessary reducing and dyeing chemicals, such as hydrosulphite of sodium, caustic soda and common salt, all traveling together, the materials, dyes and solutions through the narrow channels or orifices until the dye action is complete. By dyeing these colors in such a confined fluid medium which travels with the material throughout the machine in close contact with each other, the material is surrounded by a thin layer of solution. The reduction and dyeing action takes place in such a confined area that complete exhausts of dyes are obtained in a minimum space of time, producing results that heretofore have not been accomplished in the practical art of handling the groups of dyestuff mentioned. This is particularly true in the dyeing of what is known to the trade as heavy or dark shades of vat colors; such were still best applied by what is known as either jigg or pad-jigg method of dyeing. In this process it is necessary to pass the material a number of times back and forth through the solution in order to properly obtain the correct shade and fastness and during these passages, portions of a various

color combination may come off or go back on unevenly producing unpredictable results. In producing these same heavy shades by this invention the pigment color either in dispersed or soluble form is first applied to the fabric and then carried or passed through this machine either in one continuous operation or as a separate treatment by the material having contained the unfixed dyestuff. The colors must be put in a soluble form by reduction as the dyes of this group of colors are made soluble by entering them into a reducing solution. They have a natural tendency to bleed out into the area of fluid into which they are immersed. By this invention they are immersed in such a thin layer of solution, the dyeings are forced in contact with the material preventing this bleeding off into an area of solution which is a major factor in producing true shades by holding the dyestuff on the material, by running it through the closely fitted channels which prevent the dyes, as they become soluble, to leave the material and bleed out into a wide area of fluid. As this group of colors has been passed through this machine where the reducing and dyeing action takes place, they are either then in a separate or in a continuous operation, washed and oxidized in the usual manner necessary to treat this class of dyestuffs.

Additionally I may carry out the dyeing and developing of the naphthol or insoluble azo group of colors represented as a group by naphthol as (beta-hydroxynaphthoic acid anilide) developed with fast scarlet salt GGN (stabilized diazo salt of 2,5-dichloroaniline) and naphthol AS-G dicetooacetic tolidine developed with fast red B base 5-nitro-4-aminotoluene. The same principles offer their advantages in this field where materials must be brought in contact with chemicals or developers to produce a chemical reaction or completion of process. The materials to be treated are carried together with the chemicals through this continuous dyeing and developing unit in close contact in the confined areas as shown, which produce, due to their design, results much more satisfactory than any of the other conventional continuous methods now employed in the art.

From the above detailed description it will be apparent that I have devised a method of dyeing, developing and treating fabrics with chemicals by continuous movement of the fabric, the liquid and chemicals through a confined area so that the fabric is evenly surrounded by liquid. The close contact forces the material in the liquid to react with the fabric. This process results in improvements and advantages and simplifies the control in production in dyeing and chemical treatment. It also gives greater economy in the use of the chemicals and dyes by utilizing a very low ratio of liquid to the fabric treated.

The invention is supplemented by the novel and improved apparatus including the removable baffles and attached immersion rolls which block exposure of all but a thin area of the liquid. Many minor details in the process and apparatus are possible without departing from the scope of the following claims.

What I claim is:

1. In an apparatus for chemically treating a continuous web of fabric a tank, a series of transverse vertical partitions defining wells formed therein, and arranged in groups, an inlet for treating liquid above the first of said wells, an outlet for liquid beyond the last of said wells, the final partition of each group being highest and

forming a dam for the liquid, the liquid passing over the dam, a transverse roller mounted above each partition and means for festooning the web in each well and over each roller in succession, said means arranged in said wells so as to leave a narrow restricted area through which the material and liquid must travel.

2. In an apparatus for chemically treating a continuous web of fabric a tank, a series of transverse vertical partitions defining wells formed therein, an inlet for treating liquid above the first of said wells, an outlet for liquid beyond the last of said wells, a transverse roller mounted above each partition, a removable baffle suspended in each well and arranged therein so as to leave a narrow restricted area through which the material and liquid must travel, and a roller carried by the lower end of each baffle in close proximity to the bottom of the well.

3. In an apparatus for chemically treating a continuous web of fabric a tank, a series of transverse vertical partitions defining wells formed therein and arranged in groups, an inlet for treating liquid above the first of said wells, an outlet for liquid beyond the last of said wells, the final partition of each group being highest and forming a dam for the liquid, the liquid passing over the dam, a pair of squeeze rolls mounted above each dam, a transverse roller mounted above each remaining partition and removable means for festooning the web in each well and over each roller and through the squeeze rolls in succession.

4. In an apparatus for chemically treating a continuous web of fabric a tank, an inlet for treating liquid, an outlet for the tank, means for heating the liquid in the tank, a series of transverse vertical partitions defining wells and arranged in groups, the final partition of each group being the highest and forming a dam for the liquid, a pair of squeeze rolls mounted above each dam, means for rotating the rolls, a transverse roller mounted above each other partition, baffles removably suspended in each well and rollers journaled in the lower ends of the baffles, the baffles and associated rollers restricting the free area in the wells to narrow connecting vertical passageways extending the full width of the tank and from end to end thereof.

5. In an apparatus for chemically treating and dyeing a continuous web of fabric, a tank, a series of transverse vertical partitions, forming wells, arranged so that the upper edge of each well is slightly lower than the preceding well, thereby allowing for a gravity flow of the confined fluid from one well to the other, a removable baffle closely fitting within each well, so that the web may be festooned under one baffle and over the next partition, a fitted roll at the bottom of each baffle to be used as guide rolls, the baffles being only slightly narrower than the width of the wells so as to produce a narrow confined passageway through which the festooned web passes, thereby allowing for a minimum of fluid to flow concurrently with the web.

SUMNER H. WILLIAMS.
